UNITED STATES PATENT OFFICE.

EMIL J. NIELSEN, OF ROCKFORD, ILLINOIS, ASSIGNOR TO PHENOLIC PRODUCTS CORPORATION, OF ROCKFORD, ILLINOIS, A CORPORATION OF ILLINOIS.

TOILET-SEAT-HINGE MOUNTING.

Application filed September 22, 1926. Serial No. 136,903.

This invention relates to improvements in toilet seats and more particularly the hinge mounting thereof.

The principal object is to provide a simple and practical means in connection with the hinge mounting of the seat for frictionally restraining or checking the seat in its swinging movement to and from lowered position so as to avoid the likelihood of its dropping and being cracked or possibly damaging the bowl, and for frictionally retaining the seat in its raised position to avoid accidental dropping and also to avoid bumping the wall behind the bowl.

According to my invention the posts on the bowl on which the seat is hingedly mounted provide abutments for spring-pressed friction plungers mounted in bores provided therefor in the back of the seat, the posts having rounded heads to provide track surfaces thereon for engagement by the plungers and being preferably conformed so as to provide a depression on the crown portion thereof to retain the seat in raised position by the engagement of the plungers in the depressions, the rest of the track surface being conformed to impose increasing resistance to the movement of the seat as it approaches lowered position.

The invention is illustrated in the accompanying drawing, wherein—

Figure 1 is a fragmentary side view of a toilet bowl showing the hinge mounting of the seat in connection with which my invention is illustrated, the seat being broken away to show one of the spring-pressed plungers and its raised position being indicated in dotted lines;

Fig. 2 is a plan view of Fig. 1 on a somewhat reduced scale; and

Fig. 3 is an enlarged elevational detail of one of the posts to illustrate the form of the track surface for the plunger on the head portion thereof.

The same reference numerals are applied to corresponding parts in the three views.

The invention is shown applied to use in connection with a conventional type of toilet seat 4 on a toilet bowl 5 of any suitable type. The seat 4 has a pair of hinge arms 6 projecting rearwardly therefrom having pivotal mounting on a pintle 7 received at its ends in sockets in the heads 8 of posts 9. The heads 8 have neck portions 10, as shown, to hold the seat in the usual elevated relation

to the rim of the bowl. It is well known that toilet seats and bowls, particularly in public buildings, receive rather rough treatment and as a result of the banging of the seat down onto the bowl or back against the wall there is apt to be damage done to the bowl or to the wall and frequently the seat is cracked. According to the present invention, I provide means for frictionally restraining or checking the seat in its movement to and from lowered position so that it becomes impossible for a careless individual to cause any damage. I also provide for the retaining of the seat definitely in a certain raised position so that it will not be thrown against the wall nor can it drop accidentally when once raised.

As illustrated, I provide a pair of plunger bores 11 in the seat entering from the rear side thereof in line with the heads 8 of the posts 9. Plungers 12 received in these bores are extended under the action of compression springs 13 into frictional engagement with track surfaces 13 provided on the heads 8. The ends of the plungers 12 may be suitably rounded, as shown, to avoid any likelihood of the seat catching when it is being raised or lowered. The heads 8 are of rounded form, as shown, and the track surfaces 13 are flat but follow the contour of the head 8 for the most part, departing only to the extent indicated in Fig. 3 where the portion indicated in dotted lines at 14 represents the portion of the periphery of the head removed or at least represents the variation in the contour of the head from a true round form, as in actual practice the head 8 may be molded from bakelite material and the form of the track 13 will be determined in that way. The track surface has a depression 15 at the crown of the head into which the rounded end of the plunger 12 is arranged to ride when the seat is raised, as indicated in dotted lines in Fig. 1. The depression serves to define a definite raised position as it is noticeable in raising the seat when the plunger rides into these depressions. In fact it is only by moving the seat against considerable resistance that the seat may be moved past its intended raised position. There is thus no likelihood of bumping the wall and possibly marring it as well as the seat. It will also be noted by observation of Fig. 3 that the track surface commences with a given radius near the crown portion of the head

at the depression 15 and that the radius gradually increases toward the lower end of the track surface so that more and more resistance is imposed to the swinging movement of the seat as it approaches lowered position. The reason for this will be obvious. It positively avoids any likelihood of the seat being banged down onto the bowl or of its dropping from raised position. It is practically necessary to grasp the seat and move it from raised to lowered position as the seat will be held in any intermediate position due to the friction imposed by the plungers 12.

15 I prefer to provide the plungers 12 of bakelite material impregnated with graphite as I have found in actual practice that plungers of such material will ride smoothly and noiselessly on the bakelite heads. There is also less wearing away of the track surface on the bakelite heads when plungers of such material are used. However, the principal purpose in making this special provision is to eliminate the likelihood of a 25 squeaking noise in the raising and lowering of the seat which might otherwise result with the arrangement herein shown.

I claim:

1. The combination with a toilet seat having hinge arms projecting from the back thereof, and posts for hingedly mounting the same on a toilet bowl, of a plunger bore provided in said seat opening on the rearward side thereof in line with one of the 30 aforesaid posts, and a spring-pressed plunger received in said bore and extended therefrom into frictional engagement with said post for yieldingly restraining the seat

in its swinging movement to and from lowered position and for retaining the same in 40 raised position.

2. In the combination as set forth in claim 1, the provision of a post having a head portion providing a rounded surface to serve as a track for engagement by said 45 plunger.

3. In the combination as set forth in claim 1, the provision of a post having a head portion providing a rounded surface to serve as a track for engagement by said plunger, 50 said track having a depression therein on the crown of the head whereby to retain the seat in raised position when the plunger rides into the depression.

4. In the combination as set forth in claim 55 1, the provision of a post having a head portion providing a rounded surface to serve as a track for engagement by said plunger in swinging from raised to lowered position and commencing with a portion of a given 60 radius at the crown portion and increasing in radius from this point toward the lower end of the track whereby to impose greater resistance to the movement of the seat as it approaches lowered position.

5. In the combination as set forth in claim 1, the provision of said post having a head portion of bakelite material providing a track surface for engagement by said plunger and the provision of said plunger 70 of bakelite impregnated with graphite arranged to ride in frictional engagement with said track surface.

In witness of the foregoing I affix my signature.

EMIL J. NIELSEN.
